THOMAS HOLT, OF TRIESTE, AUSTRIA.

Letters Patent No. 80,956, dated August 11, 1868; patented in England, June 10, 1867.

IMPROVEMENT IN STEAM-GENERATORS.

The Schedule referred to in these Letters Patent and making part of the same.

TO ALL WHOM IT MAY CONCERN:

Whereas I, THOMAS HOLT, of Trieste, in the Empire of Austria, engineer, have invented "Improvements in the Construction of Steam-Boilers," I do hereby declare that the following is a full and exact description of the said improvements.

The object of this invention is to obtain an increased heating-surface in stationary, marine, and locomotive steam-boilers, and at the same time to simplify the construction of such boilers. This end I attain by the use of a novel arrangement of flattened tubes or chambers, which form the passages or flues for the flame and heated gases to pass through, while the water circulates freely between them. The tubes or chambers are set parallel to each other, and in such relative positions that an easy access to the rivets used for connecting the tubes or chambers together will be provided, and the surfaces of the tubes or chambers, by contracting and expanding under variations of temperature, will tend to prevent the adhesion of scale or deposit.

In the accompanying drawings I have shown five different arrangements of boilers with my invention applied thereto, for the purpose of illustrating the adaptability of the invention to very varying circumstances. In constructing a high-pressure land-boiler, I use, by preference, a cylindrical shell, either vertical, as shown in Sheet I, or horizontal, as shown in Sheet II, and I form a compound central flue therein by the use of the parallel tubes.

In Sheet I, Figure 1 shows in central section a vertical high-pressure land-boiler, and Figure 2 is a transverse section of the same.

A is a cylindrical shell, closed at top by an inverted cone, which is made removable, to allow of the withdrawal of the parallel tubes in a body, for repairs. At bottom the shell A is extended by a slightly conical continuation.

B B' are the tube-plates, set parallel to each other, but at an incline, for the purpose to be presently explained. The lower tube-plate, B', forms the top of the fire-chamber C, the fire-bars of which are shown at D. The water-space of the boiler extends down to a level with the fire-bars, and it is to the inner casing, A', forming the perimeter of the fire-chamber, that the tube-plate B' is secured.

E are the flattened tubes, set vertically in the middle of the shell of the boiler, and forming flues, for the passage upwards of the gases of combustion, while they present a large heating-surface around and over which the water is free to circulate.

The construction of these tubes admits of modification, but in all cases the tubes, when riveted together at their opposite ends, must allow of a free passage between them for the circulation of water over the greater portion of their length.

Figure 3, Sheet I, shows detached, and in perspective, the form of tube which I generally prefer to employ, the tube having expanded ends.

Figure 4 is a cross-section of the same, showing an arrangement for preventing the buckling, or retaining the parallelism of the sides.

Figure 5 is a perspective view of two tubes riveted together. These tubes have also expanded ends, but different means for preventing the buckling inwards of the sides of the tubes.

Figure 6 shows in perspective two tubes made parallel from end to end, and yet riveted together, so as to provide for the free circulation of water between them.

The tubes E may be formed by flattening drawn tubes, or of plates riveted, welded, or brazed together at their edges. Figs. 3 and 4 show the tubes composed of plates, riveted to side-pieces. Within the tubes, at given distances apart, I insert stays, which may be longitudinal, as shown in figs. 5 and 6, or simply balls placed in cups, formed at given distances apart by indents made in the flat sides of the tubes, and intended for holding the stays in position. Ribs may also, if preferred, be rolled on the plates used to form the tubes, and the ribs of two plates being brought together, will form stays requiring no connection or attachment. This form of stay is illustrated by Figure 7, which will hereafter be more particularly referred to.

The tubes, however made, are so arranged with respect to each other that their extremities will form, when connected together, inclines, the ends of the tubes from the first to the last being advanced, the one beyond the other, so as to expose and give access to the lines of rivets by which the adjacent tubes are securely riveted together, and caused to close the ends of the water-spaces left between the tubes, as shown at fig. 1, Sheet I. The group of tubes thus formed is then secured to the tube-plates, which are properly shaped to receive the group. The form of the group itself will be determined by the space allowed for it in the shell, it being understood that the water must circulate around the group as well as between the individual tubes.

In Sheet II, which illustrates the horizontal land-boiler—

Figure 1 is a longitudinal section of the boiler, and

Figure 2 shows in partial front view and in partial transverse section a pair of horizontal land-boilers.

In this arrangement, the tube-plates form the ends of the cylindrical shell A, and the mouths of the tubes are presented at the requisite angle to admit of the ascending flames and heated gases from the fireplace turning easily into the rear ends of and passing along the horizontal flues to the front.

In order to increase the circulation of the water, I give the horizontal flues a cant transversely, as shown at fig. 2, wherein the tubes are represented, the one half in cross-section and the other half in end view. The water-spaces between the tubes being thus transversely on the incline, the escape of the steam from the raised side will be greatly facilitated. The angle best suited in this arrangement for the turning in of the flame and heated gases to the flues at one end, and their escape at the other, gives access also to the line of rivets by which I secure the tubes, the one to the other, and when any tube is burned out, it can readily be removed by cutting away the rivet-heads, and replaced by a new tube.

To facilitate the removal of the compound tubular flues, I make in the brick-work opposite the tubes a door, F, and of sufficient size to allow of their being taken out in a body. I also avail myself of the escaping gases of combustion to superheat the steam generated in the boiler by connecting with the steam-space a cylinder, G, and conducting the escaping gases through the flue containing this chamber. The steam may be taken from this superheating-chamber at any convenient part thereof.

For improving the evaporating power of marine boilers of the ordinary construction, I propose to fill the ordinary flue-space with tubes arranged, as described, with respect to the horizontal land-boiler. This arrangement is illustrated in Sheet III, where fig. 1 is a partial front elevation and partial transverse section, taken in two different planes, of the marine boiler, and fig. 2 is a longitudinal section of the same.

The ordinary flue-spaces, it will be seen, are filled with groups of the flattened tubes E. The flame and heated gases enter at the rear ends of the tubes, and make their exit at the front ends, as in Sheet II, to the escape-flue. An incidental advantage of this arrangement of flues is that the transverse tie-rods H may be passed at any required level through the water-spaces in the groups.

Another arrangement which I propose to employ in adapting my invention to marine boilers is shown in Sheet IV, wherein the flattened metallic parallel flues are modified in form, and are secured directly to the top of the furnace. Fig. 1 shows the boiler and furnace in longitudinal section, and fig. 2 is a partial transverse section. Instead of the flues being open at their opposite ends, one side only of the flues E is open, and a division is made in them as shown at E', extending to about one-half their depth. This is most conveniently effected by forming an indented line in corresponding positions in their side-plates, the indents being sufficiently deep to insure the raised surfaces coming in contact, and thus preventing the flame and heated gases from passing between the plates at that part. Thus a bridge will be formed in each flue or chamber E for the flames to play over, as shown in the drawing. The chambers E are set up in a vertical plane, and are canted, so as to present their open mouths at an incline to the flame. A hollow or water-bridge, I, forming the roof of the front part of the fireplace C, extends to the bridge or division E' in the flue-chambers E, and the flame and gases are thus caused to pass into the chambers, and burn over the divisions therein, and escape on the other side of the bridge to the uptake flue.

The lips of the chambers are provided with flanges, by which, through the lines of rivets, they are connected together, as shown in the detached view, fig. 7, Sheet I, which represents three such chambers riveted together. The division in the chambers, instead of being formed by indenting the metal of the adjacent plates, as shown in fig. 7, may be made by inserting a stay-bar therein.

For securing the series of chambers in place, tie-rods, K, are used, and the flanges of the chambers are riveted directly to the top of the fire-chamber C. To allow of the removal of the chambers from the boiler, the bridge, I, which, being hollow, is connected at its opposite sides to the water-spaces, is made removable, it being supported in its place on angle-irons.

In applying my invention to locomotive-boilers, I incline the tube-plates B B' towards the top of the fire-chamber, and fill the space between the tube-plates with the flattened tube-flues E. These tube-flues I place horizontally, and connect them together by lines of rivets, as in the above-described land-boilers; I also cant them on one side to increase the circulation. This arrangement is shown in Sheet V, fig. 1 being a longitudinal section of the locomotive-boiler and furnace, and fig. 2 a transverse section, taken in two different planes for the purpose of showing the front ends of the tubes, and also the tubes in section. I connect the tubular flues E to the tube-plates by forming lips or flanges on the tube-plates to embrace the tubes, and to receive rivets which are passed through the sides of the tubes. At the top of the fire-box or furnace C, I provide a series of vertical flue-chambers, E*, open only at bottom, like those used in the marine arrangement, Sheet IV. These chambers E* project upwards through the water-space into the steam-space, and afford an increased heating-surface to the water, while they serve also to superheat the steam in the steam-space. These chambers are riveted by means of their flanges to the top plate of the fire-box, and they are further secured in position by

rods, K, pendent from the crown of the steam-chamber. Access to the tubes E may be obtained in the usual way by a door in the smoke-box.

Having now explained the nature of my invention, I wish it to be understood that I claim—

1. The combination of the inclined flues F, dividing-plate E', and the removable diaphragm I, in the marine boiler, as herein described, for the purpose specified.
2. The combination of the flattened tube E, composed of metallic plates having expanded ends, and braced internally by the bolts or bars, said tubes being riveted together at their ends to leave water-passages between their adjacent sides, as herein described, for the purpose specified.

In witness whereof, I, the said THOMAS HOLT, have hereunto set my hand and seal, this nineteenth day of September, in the year of our Lord, one thousand eight hundred and sixty seven.

THOMAS HOLT. [L. S.]
